[57] ABSTRACT

A female electrical contact member having a noncircular socket passage therethrough and adapted to receive a male member with a similar noncircular cross-sectional configuration. The female contact member includes a plurality of twisted beams having internal tracking surfaces which are adapted to exert a torsional force on the associated male contact as it is inserted through the passage.

SHEET 1 OF 2

ELECTRICAL CONNECTOR

BACKGROUND OF THE INVENTION

One of the primary objectives in the construction of electrical connections of the male and female socket type, particularly those connections to be used in miniature environments, is the maximization of aggressive electrical contact between the male and female members while minimizing the physical dimensions of the connection. Prior art efforts to design such electrical connections have primarily centered around the concept of providing a spring element which is bent in toward the axis of the female socket member and which is radially compressed as the male member passes through the bore of the female member. Such a system provides a variable spring deflection and surface contact depending on the tolerance of the parts. Another prior art electrical connector uses a pair of cantilever V-shaped springs extending transversely of the male member rather than longitudinally and is an effort to insure low linear engagement of the spring member to the male member to reduce dimensions of the connection.

SUMMARY OF THE INVENTION

The socket connector of this invention advantageously provides torsion spring forces acting on an associated male member serving to increase the electrical contact and retention forces in the connection. The unique torsional forces are provided through the use of a plurality of beams twisted along a longitudinal extent of the socket member. The beams are provided with internal mating surfaces which form tracking elements to apply positive twisting forces to the male contact member as the male member is inserted into the bore of the socket contact.

It is therefore an object of the invention to provide a socket contact which exerts a torsional or twisting force on a pin member.

It is another object of the invention to provide a positive gripping connection over a relatively large contact area with a mating male contact member.

An advantage of the present invention is the use of twisted track members to retain a pin within a socket and to provide an aggressive electrical contact between the two members.

These and other objects and advantages of the invention will become apparent when the following detailed description is read in conjunction with the drawings.

BRIEF DESCRIPTION OF THE DRAWINGS

FIG. 1 is a perspective view showing a typical application of the connectors of the present invention.

FIG. 2 is a side elevation view of one embodiment of the connector of the invention shown prior to association with a male contact.

FIG. 3 is a sectional view taken along line 3-3 of FIG. 2.

FIG. 4 is a side elevation view of the connector shown in FIG. 2 after the socket connector has been associated with a male contact member.

FIG. 5 is a sectional view of the connection taken along line 5-5 of FIG. 4.

FIG. 6 is a side elevational view of the contacts shown in FIG. 2 and viewed from a plane rotated ap-

proximately 45° from the longitudinal plane shown in FIG. 2.

FIG. 7 is a side elevation view of another embodiment of the present invention.

FIG. 8 is a sectional view taken along line 8-8 of the contact shown in FIG. 7.

FIG. 9 is a top view of the connector shown in FIG. 7.

FIG. 10 is a side view, similar to FIG. 7, showing a male connector associated with the contact member.

FIG. 11 is a cross-sectional view taken along line 11-11 of FIG. 10.

FIG. 12 is a side elevation view of yet another embodiment of the invention.

FIG. 13 is a cross-sectional view taken along lines 13-13 of FIG. 12.

FIG. 14 is a top view of the connector shown in FIG. 12, after the socket connector has been associated with a male contact member.

DESCRIPTION OF THE PREFERRED EMBODIMENTS

Turning first to FIG. 1, there is shown a pair of connection modules 10 and 12 which represent a typical application of the contact socket of the present invention. Module 10 includes a plurality of such socket members 14 arranged to be associated with male contact members 16 in module 12. Suitable conductor wires 18 are attached to both the socket and pin members 14 and 16, respectively.

FIGS. 2-6 clearly show one embodiment of contact socket 14. Socket 14 includes a front sleeve or ferrule portion 22 and rear sleeve or ferrule portion 24 interconnected by a plurality of beam members 26. FIG. 3 shows that the beams 26 are elongated, channel-like members, circumferentially spaced about the axis of the bore extending through the socket. The ferrule portions 22 and 24 are shown as a polygon having four sides with the beams 26 essentially being extensions of the corners 30 and 32 of the respective front and rear sleeves. Turning again to FIG. 3, it is important to note that the beams are angle members with inner surfaces formed from longitudinally extending flat surfaces intersecting at an apex 28. These inner surfaces and apices 28 form tracks in which associated corners of the spare shaped pin 16 will follow as it is inserted through the socket. The rear sleeve 24 is shown to be angularly twisted or rotated out of alignment with the front sleeve 22. The beam members 26 are similarly twisted out of alignment with the corners 30 of the front sleeve. The contact 14, rear portion 24 and beams 26 are in the twisted position shown in FIG. 2 prior to the insertion of a pin and when the pin 16 is inserted therethrough the beams as shown in FIG. 3 will be twisted in a clockwise direction to assume the position of FIG. 5. However, since the beams are biased toward their twisted position, they will exert a constant twisting or torsion force on the pin 16 through the positive engagement of the apices 28 and associated inner surfaces of the beams 26 and the corners of the pin 16. This torsion force applied to the pin serves to provide firm, aggressive electrical contact between the two contact members and further to provide a strong mechanical gripping force tending to retain the pin 16 in the socket.

FIG. 6 is another side view of the connector shown in FIG. 2 but taken along a plane disposed approximately 45° from the longitudinal plane of FIG. 2. Thus,

it is apparent that the front and rear barrel portions 22 and 24 are similar in configuration but are not angularly aligned with each other. The tab means 25 extending rearwardly from the rear barrel portion enables conductors 18 to be attached to the contact 14 in a conventional fashion.

The beam members 26 are circumferentially spaced from one another by apertures 35. However, cantilever spring members 34 are provided to extend between at least a pair of beams 26 and are normally biased radially outwardly from the contact member 14. The contact shown in FIGS. 2-6 is adapted to be inserted and locked in a block 38 or a module such as 10 in FIG. 1. The block 38 may be provided with a cavity having front and rear portions 40 and 42, respectively. The front cavity 40 has a cross-sectional configuration which is complementary to the polygonal cross-sectional shape of the ferrules 22 and 24. The contact 14 is inserted into the cavity from the left as shown in FIG. 2 until the spring members 34 snap out behind a shoulder between the front and rear cavities and until the abutment lugs 36 abut the outer face of the block. The retaining springs 34 and lugs 36 thus serve to lock the member within the cavity. It should be noted that this embodiment of the invention will be twisted as it is inserted into the cavity but will readily resume its normal biased position once it is disposed in the manner shown in FIG. 2.

FIGS. 7-10 describe a further embodiment of the invention incorporating the basic principles described above. Socket contact 14a includes front and rear ferrule portions 22a and 24a interconnected by a torsion spring section, including a plurality of beams 26a. In this embodiment, the corners of the front and rear ferrules are aligned while the beams 26a are twisted out of alignment with the corners of each ferrule portion. The internal surfaces of the beams again intersect at an apex 28a and act as tracking surfaces for the associated pin member 16a in a manner similar to that described above. The cavity in the housing 38a is of a polygonal shape complementary to the cross-sectional configuration of the contact 14a, but the rear portion of the cavity is, of course, of a cross-sectional area large enough to allow the beams 26a to be twisted during insertion of the male contact member.

Contact member 14a is designed to be inserted from the front of the module or from the right of the cavity shown in FIG. 7. Spring members 34a compress upon entering the cavity and spring back into locking engagement with a shoulder in the cavity. These spring members 34a are also retained in a longitudinal slot 44 thus stabilizing the contact within the cavity. Lug members 36a serve to limit the insertion of the contact in the cavity, as well as providing a slightly flared aperture aiding in the insertion of the pin in the socket. During insertion of the contact 14a within the complementary cavity, the beam sections 26a will be required to twist against their normal bias and return to the position of FIG. 7. FIGS. 10 and 11 represent the configuration of the contact when it is associated with a pin member. The beams 26a will exert a constant twisting force on such a pin.

Yet another embodiment of the invention shown in FIGS. 12-14 is adapted to be inserted from the rear of the module or housing. Contact member 14b is insertable from the left of the FIG. 12, first passing through a rear cavity 42b and retained in an operative position

by flexible spring retaining members 34b. Members 34b are retained in slots 44b in the front cavity 40b and abut the shoulder between the front and rear cavity. Abutment lugs 36b limit the axial insertion of the contact member in the cavity and are seated in radially extending slots, as shown in FIG. 14, retaining members 34b and 36b serving to also prevent relative rotation of the contact within the cavity.

The contact itself includes front and rear ferrule portions 22b and 24b having a polygonal configuration and including corner portions 30b and 32b. The corner portions of the front and rear barrels are shown to be angularly misaligned originally as shown clearly in FIGS. 12 and 13. The ferrule portions are integrally attached to one another through the torsion spring section including a plurality of beamlike members 26b. The beamlike members, in a manner similar to the above described embodiments, include internal tracking surfaces which are essentially extensions of the internal corners of the barrel portions.

While the invention has been described above in connection with several embodiments, one skilled in the art will appreciate that the invention is not necessarily limited to the embodiments described herein and that it is not intended to limit the invention to such embodiments. On the contrary, it is intended to cover all alternatives, modifications and equivalents as may be included within the spirit and scope of the invention as defined by the appended claims.

I claim:

1. A female electrical contact member adapted to receive a corresponding male contact member, said female member including at least one ferrule portion having a polygonal bore therethrough, a plurality of beams extending longitudinally from the ferrule portion, each beam comprising a pair of intersecting surfaces forming an internal corner, the corners of the beams forming longitudinal extensions of corner sections of the polygonal bore, said corner section extensions being twisted at least partially along their length thus being angularly displaced from the respective corners of the ferrule portion, wherein the insertion of the corresponding male member through the ferrule and beams twists the beams into alignment with the corners of the bore and creates torsional stress on the male member substantially throughout the length of the contact of the male member with the twisted beams.

2. A contact member in accordance with claim 1, which includes a front and rear ferrule portion interconnected by the plurality of beams.

3. A contact member in accordance with claim 1, wherein the polygonal bore is rectangular in cross-sectional configuration.

4. A contact member in accordance with claim 1, wherein ferrule portions are located at opposite ends of the bore and are interconnected by the plurality of beams, the ferrule portions being displaced angularly relative to the axis of the bore.

5. A contact member in accordance with claim 1, which includes cantilever spring members extending radially from the ferrule portion to retain the contact member in an appropriate cavity.

6. A contact member in accordance with claim 5, which includes abutment lugs extending radially from a ferrule portion to limit axial movement of the contact member in one direction while the cantilever spring

member limits axial movement in the other direction.

7. A contact member in accordance with claim 1, wherein a pair of polygonally shaped ferrule portions are located at opposite extremes of the bore with the corners of the ferrule portions being in angular alignment.

8. A female contact having a longitudinal passage extending therethrough for the reception of an associated male contact, said female contact comprising a noncircular barrel portion at one end and having a noncircular bore therethrough, the bore including a plurality of longitudinally extending internal tracking surfaces to nonrotatively mate with complementary external tracking surfaces extending along the length of an associated male contact, torsion beam means extending from the barrel and generally along the longitudinal passage, the internal surfaces of the beam means forming corners which are extensions of the internal tracking surfaces and which are twisted out of radial alignment with the internal tracking surfaces to provide torsional stress on the male contact as it is inserted through the beam means as the corners of the beam means are twisted into radial alignment with the internal tracking surfaces.

9. A socket contact in accordance with claim 8, wherein the beam means comprises a plurality of elongate angle members opening toward the central axis of the contact and spaced circumferentially around the axis.

10. A socket contact in accordance with claim 9, wherein a longitudinal segment of each angle member is twisted about a longitudinal axis.

11. A contact member in accordance with claim 8, in combination with a housing wherein the housing is provided with a cavity to accommodate the contact member, the cavity including an axially extending portion having a cross-sectional configuration generally complementary to the noncircular barrel portion of the contact to retain the barrel portion therein against relative rotary motion as the associated male contact is inserted therein.

12. The combination claimed in claim 11, wherein the cavity includes a shoulder means extending radially therein and the contact including resilient spring means extending radially outwardly adapted to radially compress as the contact is inserted through the shoulder means and to provide means preventing removal of the socket from the cavity.
